UNITED STATES PATENT OFFICE.

ALFRED COTTON, OF NEWARK, NEW JERSEY.

DOOR-SECURING MEANS.

No. 822,180.

Specification of Letters Patent. Patented May 25, 1908.

Application filed November 6, 1908. Serial No. 461,284.

To all whom it may concern:

Be it known that I, ALFRED COTTON, a subject of the King of Great Britain, and resident of the city of Newark, county of Essex, and State of New Jersey, have invented certain new and useful Improvements in Door-Securing Means, of which the following is a specification, reference being had therein to the accompanying drawings, in which—

Figure 1 is a front elevation of the door and its supporting frame, the head of one of the securing bolts being removed to more clearly show the construction of the door; Fig. 2 an enlarged side elevation; Fig. 3 a still more enlarged detail side elevation of a portion of the door; and Fig. 4 a detail horizontal sectional view on the line IV—IV of Fig. 1, on the same scale as Fig. 1.

This invention relates to door-securing means particularly applicable to ashpit doors used in the closed ashpit system of forced-draft furnaces, but, of course, it is to be understood that it may be used for a variety of other purposes such as doors for charging furnaces, or heating chambers, or for gas producers, coal hoppers and the like.

One of the main objects of the invention is to provide means whereby the gravity of the door will hold it tightly against the frame through which the door opening is formed.

A further object of the invention is to provide adjustable means whereby the door may be so adjusted as to fit accurately around the edges of the door opening.

Referring to the various parts by numerals, 1 designates the frame of the door. This frame may be a separate plate bolted to the furnace wall, or it may be the wall itself. Through this frame is formed the usual door opening and around the edges of this opening is formed a marginal flange 2 which forms a seat for the door. The door 3 is formed with an inwardly extending corresponding flange 4 which is fitted accurately against the outer surface of the flange or seat 2 so as to form a tight joint therewith.

In the frame 1 near the sides of the door opening are forwardly extending bolts 5, each of said bolts being provided with a lock nut 6 which bears against the plate or frame 1. The inner sides of the heads 7

of these bolts are inwardly beveled, said inner sides being cone-like as shown clearly at 8 in Fig. 3.

The door 3 is provided on each of its side edges with lateral enlargements 9 which, when the door is in position, fit loosely between the bolts 5. The lower ends of the enlargements 9 are downwardly beveled, as at 10, said beveled edges forming guiding means to center the door between the bolts and over the door opening. The upper end of each enlargement 9 is extended laterally to form the lugs 11 which extend into the path of the bolts 5. The outer faces of these lugs, at their lower ends, are downwardly and inwardly beveled, as at 12, (shown clearly in Fig. 3) said beveled surfaces being adapted to engage the correspondingly inclined inner surfaces of the bolt heads 7. The result of this construction is that the weight of the door causes the lugs 11 to slide downwardly and inwardly on the inclined inner faces of the bolt heads until its flange 4 seats squarely against the outer surface of the flange 2 of the frame. A handle 13 is preferably provided for lifting the door into and out of position.

It will readily be seen that the bolts 5 may be so adjusted as to secure the proper fit between the door and the door seat. It will not be necessary to so cast the parts that they will accurately fit; neither will it be necessary to exercise special care in the manufacture of the parts, as the bolts may be readily adjusted to secure the proper fit of the door and to prevent the lugs 11 from contacting with the bolts 5. It will also be readily understood that should the marginal flange or seat on the frame, or the flange on the door or the inclined face 12 or cone 8 wear to any considerable degree the bolts may be adjusted inwardly to compensate for said wear and to secure a tight joint between the door and the frame.

It will be noted that very little fitting is necessary to adjust this door to the door opening, the adjustment being made by setting the bolt 5 and locking it with the nut 6. When any wear takes place the bolts 5 are simply re-set and relocked. It will, therefore, be seen that said door is efficient, cheap and simple in construction and operation.

Having thus described my invention, what

I claim as new and desire to secure by Letters Patent is:—

1. The combination of a frame formed with a door opening, a gravity door formed with two outwardly extending beveled lugs on its side edges, bolts mounted in the frame one at each side of the door opening and adapted to be adjusted toward and from the frame, each of said bolts being formed with a head on its outer end, said head being conical on its inner surface and adapted to be engaged by the beveled lugs on the door, whereby said door will be directed inwardly toward the door frame, and guiding enlargements on the sides of the door to center the door between the bolts. 40
- 15 2. The combination of a frame formed with a door opening, a gravity door formed with two outwardly extending lugs on its side edges, a bolt rotatably mounted in the frame at each side of the door opening, each 45 of said bolts being formed with a head on its outer end, said head being conical on its inner surface and adapted to be engaged by the lugs on the door, whereby said door will be directed inwardly toward the door frame.
- 20 3. A frame formed with a door opening, a gravity door formed with two outwardly extending beveled lugs on its side edges, a bolt rotatably mounted in the frame at each side of the door opening, each of said bolts 50 being formed with a head on its outer end and adapted to be engaged by the beveled lugs on the door, whereby said door will be directed inwardly toward the door frame.
- 25 4. A frame formed with a door opening, a 55 gravity door formed with two outwardly extending beveled lugs on its side edges, a bolt rotatably mounted in the frame at each side of the door opening, each of said bolts 60 being formed with a head on its outer end and adapted to be engaged by the beveled lugs on the door, whereby said door will be directed inwardly toward the door frame.
- 30 4. A frame formed with a door opening, a 65 gravity door formed with two outwardly ex-

tending beveled lugs on its side edges, a bolt rotatably mounted in the frame at each side of the door opening, each of said bolts being formed with a head on its outer end, said head being conical on its inner surface and adapted to be engaged by the beveled lugs on the door, whereby said door will be directed inwardly toward the door frame, and guiding enlargements on the sides of the door to center the door between the bolts. 45

5. The combination with a frame formed with a door opening, a gravity door formed with two outwardly extending lugs on its side edges adapted to extend beyond the door opening, supports mounted in the frame one on each side of the door opening, each of said supports being provided with a conical portion on its outer end, said conical portion tapering inwardly toward the frame and being adapted to be moved inwardly and outwardly on the support with respect to the supporting frame, the lugs on the door extending over the supports and being arranged to engage the upper surfaces of the conical portions of the supports, whereby said conical portions will direct the door inwardly toward the door frame. 55

In testimony whereof I hereunto affix my signature in the presence of two witnesses this 4th day of November 1908.

ALFRED COTTON.
